WINDING AND REWINDING MECHANISM FOR MUSIC SHEETS OR RECORDS.

1,112,174.

Specification of Letters Patent. Patented Sept. 29, 1914.

Application filed April 23, 1908. Serial No. 428,781.

To all whom it may concern:

Be it known that I, EUGENE T. TURNER, a citizen of the United States, residing at Rock Island, in the county of Rock Island and State of Illinois, have invented certain new and useful Improvements in Winding and Rewinding Mechanism for Music Sheets or Records, of which the following is a specification.

10 This invention relates to improvements in winding and re-winding mechanism for perforated musical sheets or records for use with pneumatic playing attachments for music instruments, and the primary object 15 of the invention is to provide improved means for adjusting the record or music sheet with respect to the tracker board over which it is adapted to pass, to properly position the same to aline the apertures there- 20 in with the apertures in the tracker board.

A further object is to provide improved means for adjusting the record rolls to position the music sheet or record with respect to the tracker board while the record is passing over the tracker board and without stopping the operation of the mechanism.

25 A further object is to provide an improved form of roller adapted to center the music sheet or record and prevent it from 30 piling up at the end of the roller as the roller shifts.

35 A further object is to provide an improved device of this character which will be simple, durable and cheap in construction and effective and efficient in operation.

To the attainment of these ends and the accomplishment of other new and useful objects, as will appear, the invention consists in the features of novelty in the construction, combination and arrangement of 40 the several parts hereinafter more fully described and claimed and shown in the accompanying drawings, illustrating an embodiment of the invention, and in which,

45 Figure 1 is a front elevation, partly broken away and partly in section, of an improved device of this character constructed in accordance with the principles of this invention. Fig. 2 is a left hand end elevation, partly broken away, of Fig. 1. 50 Fig. 3 is a detail sectional view taken on

line 3—3 of Fig. 1. Fig. 4 is an enlarged detail sectional view taken on line 4—4 of Fig. 3. Fig. 5 is an enlarged detail sectional view on line 5—5 of Fig. 7. Fig. 55 6 is a detail elevation of the sleeve for holding one of the locking members of one of the record rollers against displacement. Fig. 7 is an enlarged detail sectional view partly in elevation of the locking mechanism for locking one of the rollers to the operation mechanism. Fig. 8 is a view of the elastic band or collar which holds the bearing sleeve in place.

60 Referring more particularly to the drawings and in the present exemplification of the invention a suitable frame comprising side members 10 and a top and bottom member 11, 12 is provided, which frame is supported in any suitable manner within the 65 casing of the instrument and in any desired position convenient for the operator. Within the frame thus formed is an upright member 13 which is spaced a short distance from one of the end members 10, preferably 70 the right hand end, and secured between the member 13 and the left hand member 10 is a tracker board 14, which is preferably 75 located midway of the top and bottom members 11, 12. This tracker board 14 is pro- 80 vided with the usual apertures 15 and connected with the respective apertures are flexible tubular members 16 which are also connected to the pneumatics which operate the piano action and which are not shown in 85 the drawings.

85 The ordinary perforated record sheet 17 is held upon a spool or roller 18 and passes over the tracker board 14 in the usual manner and is wound upon a receiving roller 19, 90 which latter is preferably crowned, that is, the diameter of the roller at the center thereof is greater than the diameter at the ends, so that when the record is rolled thereon from the roller 18, it will be centered 95 with respect to the roller and prevented from piling up at the ends of the roller as the latter is bodily shifted in a manner to be set forth. The roller 19 is provided with axles or trunnions 20 which are loosely journaled in suitable bearings 21, one of which is supported by the end member 10 and the 100

other by the member 13 and these trunnions or axles 20 are of a length to extend for a short distance beyond the respective bearings whereby the roller 19 may be shifted 5 longitudinally in its bearings to vary the position of the roller with respect to the tracker board 14. A suitable cotter or pin 22 projects through one extremity of the trunnion 20 beyond the end member 10 of 10 the frame to prevent the trunnion from being displaced with respect to its bearing. Secured to the free extremity of the other trunnion 20, beyond the member 13, is a gear wheel 23 which may be held in position 15 in any desired or suitable manner, preferably by means of a fastening screw or bolt 24 passing through a collar 25 on the gear 23 and engaging the axle or trunnion 20. This gear 23 is adapted to mesh with an 20 elongated pinion 26, which is secured to the extremity of a flexible rotary shaft 27, which latter passes through a suitable aperture 28 in the adjacent end member 10 of the frame so that when the shaft 27 is rotated 25 a rotary motion will be imparted to the receiving spool or roller 19 to wind the record sheet 17 thereon as it is paid out from the roller 18. The aperture 28 in the member 10 is adapted to permit the shaft 30 27 to be flexed by means of a suitable operating rod 29 connected to the collar 30 which surrounds the shaft 17 to move the pinion 26 out of engagement with the gear wheel 23.

35 The roller 18 is provided with a trunnion 31 projecting from one extremity thereof, which is journaled in an adjustable bearing 32, which latter is supported by the end member 10 and is adapted to move longitudinally in a suitable bushing 33. Secured to the outer face of the member 10 is an elastic member 34 preferably in the form of a leaf spring, one extremity of which engages the outer extremity of the bearing 32. Projecting from the opposite extremity of the roller 18 is a trunnion 35 which is provided with the ordinary laterally projecting lugs 36 adapted to project through suitable slots 37 in a bearing 38 when the extremity of the 40 trunnion 35 is seated in the bearing so that the rotation of the roller will impart a rotary motion to the bearing 38. The bearing 38 is provided with a projecting shank or trunnion 39 extending from the opposite 45 face and at the diametric center thereof and this shank or trunnion projects into a sleeve 40 which latter is provided with a bifurcated portion 41 and a circumferential groove or recess 42 adjacent one extremity thereof, 50 preferably the extremity in proximity to the bearing 38. Secured to the opposite extremity of the sleeve 40 is a disk 43 which is of a diameter somewhat larger than the diameter of the sleeve.

55 A sleeve or bushing 44 is provided in the

upright member 13 and preferably projects for some distance beyond the face of the member remote from the roller 18 and is of an internal diameter slightly larger than the external diameter of the sleeve 40, so that 50 the latter may be inserted within the bushing to rotate freely when the roller 18 is rotated. The sleeve 40 is held against displacement with respect to the bushing 44 by means of the disk 43 which stands adjacent one extremity of the bushing and a spring clip or collar 45 which is adapted to be seated within the circumferential groove 42 in the sleeve 40 beyond the other end of the bushing. A pin or lug 46 projects laterally from the shank or trunnion 39 and extends into the bifurcation 41 of the sleeve and is preferably of a length that the extremity thereof will stand flush with the periphery of the sleeve. This pin 46 is adapted to move 85 longitudinally in the bifurcation 41 and when the bearing 38 is rotated, it will engage the side of the bifurcation to rotate the sleeve 40 within the bushing 44 and also the disk 43. The bifurcation 41 in the sleeve 90 preferably has its opening adjacent the bearing 38 and the elastic band or collar 45 which holds the sleeve 40 against displacement with relation to the bushing 44 is adapted to project across the bifurcation to 95 prevent accidental displacement of the shank or trunnion 39.

When it is desired to remove the bearing 38 and the shank 39, the elastic band or collar 45 is first removed and then the shank 39 100 may be easily drawn out of the sleeve and if desired, the sleeve 40 may be also drawn out of the bushing in the opposite direction.

Supported by the disk 43 and preferably secured to the face thereof adjacent the 105 member 13 is an elastic member preferably in the shape of a flat spring 46^a, one extremity of which is secured as at 47 to the face of the disk 43 and the other extremity 48 rests upon the head 49 of a pin or projection 50 which extends through the disk and beyond the opposite face thereof.

A bodily movable member 51 is located between the member 13 and the adjacent end member 10 of the frame. This member 115 51 is supported by means of the flexible shaft 27 which passes loosely therethrough adjacent one of its extremities, as at 52, and the member is of a length to terminate short of the bottom member 12 of the frame. The 120 upper extremity 53 is provided with an inclined slot 54 into which a lug or projection 55, supported preferably by the member 11 of the frame, extends. The slot 54 is inclined toward the member 13 so that when the member 51 is bodily depressed by means of the shaft 27 when the latter is flexed under the influence of the operating member 29, it will also move in a direction toward the member 13. Supported by this member 125 130

51 adjacent the disk 43 is a stub axle 56 upon which is journaled a sleeve 57 and supported by the sleeve is a disk 58 which is of a diameter substantially equal to the diameter of the disk 43 and is provided with an open slot 59 in the periphery thereof. The sleeve 57 is held against longitudinal displacement with respect to the stub axle 56 preferably by means of a screw or bolt 60 which passes through the sleeve and into a peripheral groove 61 in the stub axle 56. The sleeve 57 is of such a length that the disk 58 will normally stand in close proximity to the disk 43 so that when the member 51 is bodily moved, the disk 58 will be brought into close proximity with the disk 43 to permit the lug or pin 50 to enter the slot 59 and lock the disks together to permit the bearing 38 to be rotated by the rotary motion of the disk 58. Should it so happen that the disk 58 is brought into proximity with the disk 43 when the slot 59 is remote from the pin or projection 50 the latter will yield against the tension of the elastic member 46 until the slot is brought into alignment with the end of the pin or lug, at which time the latter will spring into the slot to lock the parts.

Any suitable means may be provided for rotating the disk 58 from the shaft 27. A suitable and efficient means for accomplishing this purpose comprises a sprocket wheel 62 supported by the sleeve 57, and a similar sprocket wheel 63 supported by the shaft 27, and a sprocket chain 64 surrounding the two sprockets 62 and 63.

When the parts are in the position shown in Fig. 1 of the drawings, the pinion 26 will be in engagement with the gear wheel 23 and motion will be imparted to the roller 19 to wind the record 17 thereon from the roller 18. When it is desired to re-wind the record upon the roller 18, the shaft 27 is flexed by means of the operating member 29 so as to disengage the pinion 26 from the gear 23. This movement will bodily shift the member 51 in the manner already set forth to cause the disks 43 and 58 to become locked and also to disengage the pinion 26 from the gear 23. The disk 58 being rotated by the shaft 27, it will be apparent that when the disks are locked together, the roller 18 will be rotated in the opposite direction and the record will be re-wound thereon.

Any suitable means may be provided for shifting the record 17 longitudinally with respect to the tracker board 14 in order to properly align the apertures in the record with respect to the apertures in the tracker board and for this purpose there may be provided a pin or member 65 which is loosely supported preferably by the upright member 13. This pin or member 65 is of a length somewhat greater than the thickness 65 of the member so as to project for some dis-

tance beyond the faces thereof, one extremity being adapted to engage one face of a peripheral flange 66 on the bearing 38 and if desired, a suitable piece of fabric 67, such as felt or the like, may be secured to the member 65 to act as a brake on the spool 18. Pivotedly supported intermediate its ends on the opposite face of the member 13 is an arm or lever 68. The free extremity 69 thereof stands in close proximity to the extremity 70 of the pin or member 65 and is adapted to engage said extremity when the arm or lever is rocked so as to bodily shift the roller 18 longitudinally so as to move the bearing 32 in the bushing 33 against the tension of the elastic member 34 to slide the record 17 longitudinally over the tracker board to the desired position. When this roller 18 is thus bodily adjusted, the roller 19 will be automatically adjusted longitudinally by means of the record 17, the trunnions 20 of the roller 19 being adapted to move freely in a longitudinal direction in the bearings 21. During this bodily movement the gear 23 will move longitudinally 90 along the elongated pinion 26 to prevent accidental disengagement of the operating mechanism. The roller 19, being crowned, will cause the record to be uniformly distributed or centered thereon and will prevent the record from piling up at the ends of the roller.

Any suitable means may be provided for rocking the arm or lever 68 about its point of pivotal support 71. A suitable and efficient means for accomplishing this purpose will now be described.

An adjusting bolt or screw 72 is rotatably supported, preferably by means of the upright member 13. One extremity of this bolt or screw 72 is provided with an operating head 73 located to one side of the member 13 preferably adjacent the roller 19. The other extremity 73 of the screw or bolt projects for some distance beyond the opposite face of the member 13 and the bolt or screw is held from longitudinal displacement preferably by means of a collar or bushing 75 which surrounds the bolt or screw 74 adjacent the member 13 and is secured to the bolt or screw by means of a suitable fastening pin or member 76 passing through the collar and engaging the bolt. This collar 75 co-operates with a shoulder 77 formed by the operating head 73 of the bolt adjacent the opposite face of the member 13. Mounted to travel upon the threaded extremity 74 of the bolt or member 72 is a nut 78 which is provided with a convexed surface 79 adjacent the arm or lever 68, and projecting beyond this convexed surface is a lug or pin 80 which preferably extends parallel with the extremity of the bolt or member 72 and projects into a bifurcation 81 formed in the free extremity of the arm or 130

lever 68. With this construction it will be apparent that when the head 73 is operated to rotate the shank of the bolt or member 72, the nut 78 will be fed toward or away from the member 13 according to the direction of rotation of the operating head 73. When the nut 78 is fed away from the member 13, the bifurcated extremity of the lever 68 will also be moved away from the member 13 when the nut 78 engages and moves said extremity and when the nut 78 is fed toward the member 13 the extremity 69 of the lever will be moved in a direction away from the roller 18 to release the tension on the elastic member 34 which latter will shove or move the roller 18 longitudinally in its bearings to adjust the record 17 with respect to the tracker board. The convexed surface 79 of the nut 78 permits the lever 68 to be freely rocked and the pin or projection 80 which extends into the bifurcation 81 will hold the nut 78 against rotation with the bolt or member 72.

If desired, a suitable shield 82 may be provided for supporting the flexible tubes or members 16 which connect with the tracker board 14 and extend to the pneumatics. One extremity of the shield 82 may be secured to a suitable projection 83 on the tracker board 14 and the other extremity may be secured to a suitable support 84 on the supporting frame work and this shield 82 may be arched over the roller 19. With this construction it will be also apparent that the roller 18 may be readily removed from its bearings to permit the insertion of another roller by moving the roller 18 longitudinally to adjust the bearing 32 against the tension of the elastic member 34 sufficiently to permit the extremity of the trunnion 35 to be removed from its bearing 38. Likewise another roller may be inserted or placed in position by first inserting the trunnion 31 in the bearing 32 and moving the roller longitudinally to adjust the bearing 32 against the tension of the elastic member 34. After the trunnion 35 has been properly positioned the roller 18 may be permitted to move longitudinally in the opposite direction under the influence of the elastic member 34 until the trunnion 35 is properly seated.

In order that the invention might be fully understood, the details of the foregoing embodiment thereof have been thus specifically described, but

What I claim as new is—

1. In a device of the class described, the combination of a tracker board, a record supporting spool on one side of the board, a record receiving spool on the opposite side of the board, means for feeding the record on to the receiving spool, means for longitudinally adjusting one of the spools at will to bodily shift the record with respect to the tracker board, and means whereby the rec-

ord when thus shifted will automatically shift the other spool to position the latter with respect to the first said spool.

2. In a device of the class described, the combination of a tracker board, a record supporting spool on one side of the board, a record receiving spool on the opposite side of the board, one of said spools being crowned, means for feeding the record on to the receiving spool, means for longitudinally adjusting one of the spools at will to shift the record with respect to the tracker board, and independent means whereby the shifting of said spool will automatically shift the other spool to position the latter with respect to the first said spool.

3. In a device of the class described, the combination of a tracker board, a longitudinally adjustable record supporting spool on one side of the board, means for feeding the record to the receiving spool, elastic means for holding one of the spools in position with respect to the tracker board, positive means for adjusting said roller longitudinally and at will to position the record with respect to the tracker board, and means whereby the record when thus shifted will automatically adjust the receiving roller to position the latter with respect to the first said roller.

4. In a device of the class described, the combination of a tracker board, a record supporting spool on one side of the board, means for operating said spool, a record receiving spool on the opposite side of the board, means for operating said spool, means for longitudinally adjusting one of the spools to position the record with respect to the tracker board, means whereby the record when thus shifted will automatically adjust the receiving spool, and means for throwing one of the spool operating means into and the other out of operation.

5. In a device of the class described, the combination of a tracker board, a record supporting spool on one side of the board, means for operating said spool, a record receiving spool on the opposite side of the board, means for operating said spool, means for longitudinally adjusting one of the spools to position the record with respect to the tracker board, means whereby the record when thus shifted will automatically adjust the receiving spool, and a single means for simultaneously throwing one of the spool operating means into and the other out of operation.

6. In a device of the class described, the combination of a tracker board, a record supporting spool on one side of the board, means for operating said spool, a record receiving spool on the opposite side of the board, means for operating said spool, means for longitudinally adjusting one of the spools to position the record with respect to the tracker board, and means whereby the record when thus shifted will automatically adjust the receiving spool, and a single means for simultaneously throwing one of the spool operating means into and the other out of operation.

to the tracker board, means whereby the record when thus shifted will automatically adjust the receiving spool, a common means for imparting motion to both of said spool operating means, and a single means for throwing one of the spool operating means into and the other out of operation.

7. In a device of the class described, the combination of a tracker board, a record supporting spool on one side of the board, means for operating said spool, a record receiving spool on the opposite side of the board, means for operating said spool, means for longitudinally adjusting one of the spools to position the record with respect to the tracker board, means whereby the record when thus shifted will automatically adjust the receiving spool, a common means for imparting motion to both of the said spool operating means, and means under the control of the operator for simultaneously throwing one of the spool operating means out of and the other into operation.

8. In a device of the class described, the combination of a supporting frame, a record receiving spool provided with trunnions projecting beyond the ends thereof, journals in the frame in which the respective trunnions are mounted and free to move endwise, a record supporting spool, bearings for the supporting spool longitudinally adjustable in the frame, a tracker board between the spools, means for feeding the record across said board and onto the receiving spool, and means for adjusting the bearings of the record supporting spool to longitudinally adjust the spool to position the record with respect to the tracker board, said receiving spool being automatically and longitudinally adjusted in its bearings by the record to position the spool with respect to the record supporting spool.

9. In a device of the class described, the combination of a supporting frame, a record receiving spool provided with trunnions projecting beyond the ends thereof, journals in the frame in which the respective trunnions are mounted and free to move endwise, a record supporting spool, bearings for the supporting spool adjustably supported by the frame, a tracker board between the spools, an elastic member operatively related to one of the bearings to hold the latter in position, means for feeding the record from one spool to the other, and positive means for longitudinally adjusting the record supporting spool against the tension of the said elastic means to bodily shift the record with respect to the tracker board, said receiving spool being adapted to be automatically shifted in its bearings by the record when the first said roller is adjusted.

10. In a device of the class described, the combination of a supporting frame, a record receiving spool provided with trunnions pro-

jecting beyond the ends thereof, journals in the frame and in which the respective trunnions are mounted and free to move endwise, a record supporting spool, bearings for the supporting spool adjustably supported by the frame, a tracker board between the spools, means for feeding the record from one spool to the other, and means for longitudinally adjusting the record supporting spool to bodily shift the record longitudinally with respect to the tracker board, said means including an operating lever and an adjusting screw for rocking the lever, said receiving spool being adapted to be automatically shifted in its bearings by the record when the first said roller is adjusted.

11. In a device of the class described, the combination of a supporting frame, a record supporting spool, a record receiving spool mounted for free endwise movement, a tracker board, means for feeding the record across the board, a lever pivotally supported intermediate its ends, means other than the record operatively related to one end of the lever for rocking the same about its pivot at will, and means operatively related to one end of the supporting spool and adapted to engage the other end of the lever for longitudinally adjusting the supporting spool to automatically and bodily shift the record and the receiving spool with respect to the tracker board.

12. In a device of the class described, the combination of a supporting frame, a record supporting spool, a record receiving spool mounted for free endwise movement, a tracker board, means for feeding the record across the board, a lever pivotally supported intermediate its ends, means other than the record operatively related to one end of the lever for rocking the same about its pivot and at will, in one direction, means operatively related to one end of the supporting spool and adapted to be engaged by the free end of the lever for longitudinally adjusting the supporting spool in one direction to bodily shift the record and the receiving spool with respect to the tracker board, and means operatively related to the other end of the supporting spool for bodily moving the spool in the other direction.

13. In a device of the class described, the combination of a supporting frame, a record supporting spool, a receiving spool for the record, a tracker board between the spools, said receiving spool being mounted for free longitudinal movement, means for feeding the record across the board, a lever pivoted intermediate its ends, means operatively related to one end of the lever for rocking the same in one direction, means operatively related to one end of the first said spool and adapted to be engaged by the lever for longitudinally shifting the spool to bodily adjust the record with respect to

the tracker board, and means operatively related to the other end of the first said spool for moving the same in the opposite direction, said receiving spool being adapted to be automatically adjusted longitudinally by the record to position the same with respect to the first said spool when the latter is adjusted.

14. In a device of the class described, the combination of a supporting frame, a record supporting spool, a tracker board, means for feeding the record across the board, a pivoted lever, means operatively related to one end of the spool and adapted to be engaged by the lever, said lever being provided with a bifurcation, an adjusting screw, and a nut movable on the screw, said nut being adapted to rock the lever when the screw is rotated in one direction and being provided with a portion projecting into the bifurcation whereby the nut will be held against rotation, said lever being adapted to move the spool longitudinally with respect to the tracker board to bodily shift the record.

15. In a device of the class described, the combination of a supporting frame, a record supporting spool, a tracker board, means for feeding the record across the board, a pivoted lever, means operatively related to one end of the spool and adapted to be engaged by the lever, said lever being provided with a bifurcation, an adjusting screw, a nut movable on the screw, said nut being adapted to rock the lever when the screw is rotated in one direction and being provided with a portion projecting into the bifurcation whereby the nut will be held against rotation, said lever being adapted to move the spool longitudinally with respect to the tracker board to bodily shift the record, and separate means for returning the spool when the adjusting screw is rotated in the opposite direction.

16. In a device of the class described, the combination of a supporting frame, a record supporting spool, a tracker board, means for feeding the record across the board, a pivoted lever, means operatively related to one end of the spool and adapted to be engaged by the lever, said lever being provided with a bifurcation, an adjusting screw, and a nut movable on the screw, said nut having a convexed surface engaging the lever and being provided with a portion projecting into the bifurcation to hold the nut against rotation when the screw is rotated to rock the lever in one direction, and said lever being adapted to move the spool longitudinally to bodily shift the record with respect to the tracker board.

17. In a device of the class described, the combination of a supporting frame, a record supporting spool, a tracker board, means for feeding the record across the board, a

pivoted lever, means operatively related to one end of the spool and adapted to be engaged by the lever, said lever being provided with a bifurcation, an adjusting screw, a nut movable on the screw, said nut having a convexed surface engaging the lever and being provided with a portion projecting into the bifurcation to hold the nut against rotation when the screw is rotated to rock the lever in one direction, and said lever being adapted to move the spool longitudinally to bodily shift the record with respect to the tracker board, and elastic means for moving the spool in the opposite direction when the screw is rotated in the opposite direction.

18. A device of the class described including in combination a tracker board, a record supporting spool, an elastic bearing for one end of the spool, a rotatable and longitudinally adjustable support for the other end of the spool, means for rotating the support to impart a rotary motion to the spool to feed the record across the tracker board, means for adjusting the said support to shift the spool longitudinally to position the record with respect to the tracker board, and a spool for receiving the record, said receiving spool being adapted to be automatically shifted longitudinally by the record to position the receiving spool with respect to the record supporting spool when the latter is adjusted.

19. A device of the class described including in combination a supporting frame, a tracker board, a record supporting spool, means for supporting the spool for longitudinal adjustment including a rotatable support, said support being provided with a circumferential disk, a member independent of the support and loosely mounted in the frame, a lever, one end of which is adapted to move the said member into engagement with the disk to shift the support and spool longitudinally, means for operating the lever, and means for imparting a rotary motion to the spool to feed the record across the tracker board.

20. A device of the class described including in combination a support for the record spool, said support comprising a sleeve, a bearing telescoping with the sleeve and rotatable therewith, said bearing being capable of independent movement longitudinally with respect to the sleeve, means for locking the sleeve and bearing against separation, a bearing for the sleeve, means for rotating the sleeve, and means for longitudinally adjusting the first said bearing in the sleeve.

21. A device of the class described including in combination a support for the record spool, said support comprising a sleeve, a bearing telescoping with the sleeve and rotatable therewith, said bearing being capable of independent movement longitudinally

with respect to the sleeve, a bearing for the sleeve, means for rotating the sleeve, means for longitudinally adjusting the first said bearing in the sleeve, and a common means 5 for holding the bearing from displacement with respect to the sleeve and the sleeve from displacement with respect to its bearing.

22. A device of the class described including in combination a support for the record spool, said support comprising a sleeve having a slot, a bearing telescoping with the sleeve and being provided with a lateral projection extending into the slot, whereby the 10 bearing will be rotatable with and capable of an independent longitudinal adjustment with respect to the sleeve, a fixed bearing for the sleeve, means connected to said sleeve for rotating the sleeve, and means separate 15 from the bearing and sleeve for longitudinally adjusting the bearing in the sleeve.

23. A device of the class described including in combination a support for the record spool, said support comprising a sleeve having a slot, a bearing telescoping with the sleeve and being provided with a lateral projection extending into the slot, whereby the bearing will be rotatable with and capable of an independent longitudinal adjustment 25 with respect to the sleeve, a bearing for the sleeve, said sleeve projecting beyond its bearing, means on the sleeve adjacent one end of the bearing for rotating the sleeve, means engaging the sleeve adjacent the 30 other end of the bearing for holding the sleeve against displacement, and means separate from the bearing and sleeve for adjusting the first said bearing longitudinally with respect to the sleeve.

40 24. A device of the class described including in combination a support for the record spool, said support comprising a sleeve having a slot, a bearing telescoping with the sleeve and being provided with a lateral 45 projection extending into the slot, whereby the bearing will be rotatable with and capable of an independent longitudinal adjustment with respect to the sleeve, a bearing for the sleeve, said sleeve projecting beyond its bearing, means on the sleeve adjacent one end of the bearing for rotating the sleeve, an elastic member engaging the sleeve adjacent the other end of the bearing for preventing displacement of the sleeve, said 50 elastic member extending across the slot in the sleeve and in the path of movement of the projection on the first said bearing to prevent displacement thereof, and means for longitudinally moving the first said bearing 55 with respect to the sleeve.

60 25. A device of the class described, including in combination a support for the record spool, said support comprising a sleeve having a slot, a bearing telescoping with the 65 sleeve and being provided with a lateral

projection extending into the slot, whereby the bearing will be rotatable with and capable of an independent longitudinal adjustment with respect to the sleeve, a bearing for the sleeve, said sleeve projecting beyond its bearing, means on the sleeve adjacent one end of the bearing for rotating the sleeve, an elastic band engaging the sleeve adjacent the other end of the bearing for preventing displacement of the sleeve, said 70 elastic band extending across the slot in the sleeve and in the path of movement of the projection on the first said bearing to prevent displacement thereof, means for longitudinally moving the first said bearing with 75 respect to the sleeve, and means for preventing displacement of said elastic band.

26. In apparatus of the class described, the combination of two longitudinally movable rotary spools arranged in parallel, a record sheet adapted to unwind from one spool and wind upon the other, an intermediate tracker board across which the record passes, means for positively shifting one of said spools longitudinally, and means 80 coöperating with said record as it winds upon said spool for automatically positioning said other spool with respect to said tracker board.

27. In apparatus of the class described, the combination with a record sheet, two parallel spools adapted to be alternately positively driven to wind the record from one to the other, an intermediate tracker board across which the record passes, means 90 for positively shifting one of said spools axially, and means under the control of the moving record for automatically causing the other spool to follow the movements of the positively shifted spool.

28. In apparatus of the class described, the combination of a record sheet, a pair of longitudinally adjustable rotary spools adapted to wind the record from one to the other, a tracker board across which the moving record passes, means for adjusting one of said spools to position the record relatively to the tracker board, and means under the control of the record for causing the other spool to automatically follow the 100 movements of said adjusted spool.

29. In apparatus of the class described, the combination of a tracker board, a record sheet adapted to move across said tracker board, a longitudinally adjustable spool from which said record unwinds, means for adjusting said spool to position the record relatively to the tracker board, and a positively driven spool adapted to receive and wind the record upon itself and automatically assume a position corresponding to the 110 relative position of the record.

30. In apparatus of the class described, the combination of a record sheet and a tracker board over which said record passes,

a spool from which said record unwinds, said spool being longitudinally adjustable to position the record relatively to the tracker board, and a positively driven spool 5 responsive to the positioning movements of the record for winding the record upon itself.

In testimony whereof I have signed my

name to this specification, in the presence of two subscribing witnesses, on this 10th 10 day of April, A. D. 1908.

EUGENE T. TURNER.

Witnesses:

DAVID SEARS,
C. A. LIITT.
